[57] ABSTRACT

A musical instrument of the Xylophone type which includes a housing having a plurality of rotating wheels, each being mounted for independent rotation with respect to one another, and each including a pivotally connected striker which under the influence of centrifugal force extends radially outwardly to strike an adjacent tone bar. The respective wheels may be color or otherwise coded for use with a similarly coded song card so that a player can sequence the rotation of the respective wheels to sound the specified notes of a given song.

FIG. 7

MUSICAL INSTRUMENT

PROBLEM AND PRIOR ART

There are presently known numerous types of xylophone type musical devices which have been utilized either in toys or musical instruments. Generally the known type of xylophone type musical device comprises essentially of a rotating drum having projecting fixed fingers or pins which upon rotation of the drum causes the pins to effect the displacement of a hammer which in turn strikes a tone bar. Such devices have been typically disclosed in U.S. Pat. Nos. 3,651,731; 3,608,414; 3,456,543; 3,455,051; 2,812,680 and 1,547,183. It is also known that the projecting pins or fingers of the rotating drum of such instruments may directly strike or impinge flexible tone bars as is common in the conventional music box movements or as evidenced in U.S. Pat. No. 2,770,159.

It has been observed that sound produced by the known xylophone type devices, particularly when applied to toy devices, can be best characterized as a series of "pings" or "plunks" having at best, a "tin like ring" which often is not pleasing or pleasant, and for this reason frequently renders the recognition of a tune or song played thereby difficult, and frequently impossible.

OBJECTS

It is an object of this invention to provide a musical instrument or toy of a xylophone type which produces notes of long and pleasing duration.

Another object is to provide a xylophone type instrument in which the respective notes can be repeatedly sounded to produce alternating overlapping melodious sounds which are more pleasing than those produced by the presently known constructions.

Another object is to provide a xylophone type musical instrument which includes a series of independently rotated wheels having centrifugally actuated strikers for repeatedly sounding the tone bars as the respective wheels are independently rotated relative to the tone bar.

Another object is to provide a xylophone type musical device applicable for use as a musical toy which is safe and wherein the sharp parts are not rendered accessible to a small child.

Another object is to provide a xylophone type musical instrument in which the strikers can be readily coded to the notes of a given song so that a person or young child without any musical training can readily play a given song.

Another object is to provide for a xylophone type musical instrument which can be played with the instrument held in any position.

BRIEF SUMMARY OF THE INVENTION

The foregoing objects and other features and advantages are attained by a musical device which includes a housing which has rotatably journaled thereon a plurality of rotating members, each member being rotatably journaled so that each can be readily rotated independently of one another at the will of a player. Each rotating member has pivotally connected thereto adjacent a peripheral portion thereof one or more strikers which are each free under the influence of centrifugal force to extend radially outwardly beyond the periph-

ery of its respective rotatable member when the member is rotated.

Disposed within the housing and opposite the respective rotatable members are a plurality of tone bars. The respective tone bars are spaced from their associated rotatable member a distance sufficient so as to be struck by the striker of the associated rotatable member when the striker is extended under the influence of centrifugal force.

10 The invention further contemplates that the housing may be formed for detachably receiving a song chart having indicia formed thereon to represent the notes of a given song. The note indicia of the given song may be coded to the respective rotatable members so that a small child or person having virtually no musical training can sequence the rotation of the rotatable member to sound the notes of the given song. The arrangement of the component parts is such that a new and pleasing sound is produced which permits varying notes of long and overlapping sounds to be produced by the continued independent spinning of the respective rotatable member, which enables the associated strikers to continue to strike the respective tone bars at predetermined intervals. A handle may be provided to facilitate either the carrying or the supporting of the musical device.

FEATURES

A feature of this invention resides in the provision of a xylophone type instrument which is relatively simple in construction, which can be economically fabricated and which is positive in operation.

Another feature resides in the provision of a novel xylophone type musical instrument construction which renders it particularly applicable for use as a toy which is safe and easy to play.

Another feature of the invention resides in the provision that the construction of the instrument renders it readily applicable for use as a serious musical instrument capable of one or more octaves.

Another feature of the invention resides in the provision that the construction when applied to use as a toy enables the sharp parts to be safely shielded so as to be rendered inaccessible to a small child.

Other features and advantages will become more readily apparent when considered in view of the drawings and specification in which:

FIG. 1 illustrates a perspective view of a musical instrument embodying the present invention.

FIG. 2 illustrates a perspective view of the musical instrument illustrated in FIG. 1, but shown in a different position of play.

FIG. 3 is a side sectional view taken along line 3—3 on FIG. 2.

FIG. 4 is a detailed side elevation view of the rotating member utilized in the embodiments of FIGS. 1 and 2.

FIG. 5 is a cross section view taken along line 5—5 on FIG. 4.

FIG. 6 is a perspective view of a song chart adapted for use with the embodiments of FIGS. 1 to 5.

FIG. 7 is a perspective view of another modification of the invention.

Referring to the drawings and more specifically to FIGS. 1-5 there is illustrated therein a musical instrument 10 embodying the present invention. As best seen in FIGS. 1-3, the musical instrument 10 comprises a

base means formed to define an enclosure housing 11. In the illustrated form of invention the enclosure housing 11 is formed of a pair of complementary dish-shaped housing members 12 and 13 arranged to complement one another in the assembled position. The upper housing section 13 is formed with an opening 14.

In the assembled position, the complementary housing sections 12 and 13 may be secured by any suitable means. For example, the juncture of the respective housing may be abutted or frictionally interfitted and secured by suitable fastening means, as for example, screws, rivets 29 and the like, or the respective housing may be suitably bonded or adhesively secured to define a unitary housing enclosure.

A plurality of rotatable members 15 in the form of wheels or drums is mounted for independent rotation relative to one another within the housing 11 adjacent the opening 14. As best seen in FIG. 3 opposed trunion members 16 are suitably supported on the bottom 12A of the lower housing section 13 for supporting therebetween an axle or shaft 17 upon which the respective wheels or drums 15 are rotatably journaled for independent rotation relative to one another in side by side relationship. As best seen in FIGS. 1 and 2, each of the rotating members 15 is slightly spaced from the next adjacent wheel or drum 15 to permit rotation of the respective members 15, to occur without interfering with the rotation of the next adjacent wheel 15. While the respective rotating members 15 may be formed in any suitable manner, in the illustrated embodiment the rotating members or wheels 15 are formed of complementary members 15A, 15A, each being similar in construction, and in the assembled position they are arranged so as to be disposed in back to back relationship, as best seen in FIG. 5.

Each of the similar complementary sections 15A, 15A includes a hub portion 18, a laterally extending peripheral rim portion 19, and an interconnecting plate or spoke portion 20. Also the respective wheel portions 15A, 15A is provided with complementary pin 21 and hole 22. The arrangement is such that by aligning the pins 21 of one section 15A with the complementary holes 22 of the other section 15A, the respective complementary wheel members 15A, 15A can be snapped or press-fitted together in back to back relationship to form a unitary wheel member 15. The respective wheels 15 when assembled are supported on the axle 17.

Each of the wheel assemblies 15 is provided with one or more recesses 23 which are circumferentially spaced intermediate thereof. In the illustrated form of the invention, as seen in FIG. 4, the wheel assembly 15A, 15A is provided with two recesses 23 which are oppositely disposed. Each of the recesses 23 is formed to open to the outer periphery of its respective wheel. Extending between the side walls 23A, 23A of the respective recesses 23 is a pin or projection 24 for retaining within the recess a hammer or striker means 25. As illustrated the striker 25 comprises a member which is bent or formed at one end portion with a loop 25A by which it is pivotally secured about the recess pin 24, the other end 25B forming the portion to strike a tone bar 26, as will be hereinafter described.

The arrangement is such that the striker 25 is free to pivot about the pin 24. As best seen in FIGS. 1 to 5 the recess 23 formed in the respective wheels is sufficiently

deep to house the clapper or striker in a non-rotating position of the wheel. Upon rotation of the respective wheels 15 the centrifugal force developed thereby causes the hammer or striker 25 to be readily extended so that the free end thereof extends beyond the periphery of the wheel 15.

Within the housing, and supported on the lower complementary section thereof is a support 27 on which a series of bars 26 are mounted. The tone bars 26 are mounted in spaced relationship on the tone bar support 27 by suitable support pins 28 which may include rubber mounts or the like. The arrangement of the tone bars 26 is such that each is oppositely disposed to one of the respective wheel means 15 at a distance sufficiently spaced therefrom so that the radially extending strikers 25 extending beyond the periphery of the associated rotating member, during the rotation thereof, will preferably strike the edge portion of the oppositely disposed tone bar 26. In operation it will thus be apparent that upon rotation of the respective wheel members 15, i.e., by spinning the wheels 15 manually, will cause the associated striker or hammer 25, due to centrifugal force, to swing beyond the periphery of the wheel and continually strike the associated tone to produce a sound of long duration corresponding to the tone frequency of the associated tone bar. It will be understood that the tone bars 26 may be formed to sound the notes of the musical scale. The arrangement is such that the wheels 15 can be rotated in either direction to result in the striker 25 striking the tone bars 26.

In the form of the invention disclosed in FIGS. 1-5, the upper housing section is formed with a recess portion 30 which is formed with opposed channel shaped edges to form a slide track 31. Adapted to be detachably received within the opposed slide tracks 31, the present invention contemplates the utilization in conjunction with the musical device, of a song chart 32 having indicia 33 thereon to simulate musical notes arranged in a given melody or song. It is also contemplated that the respective notes indicia 33 be coded, as for example, by color, to the respective rotating members or wheels 15 corresponding to the given note. The arrangement is such that a person with little or no musical knowledge could effect the playing of the song of the song chart 32 by rotating the respective colored wheels 15 in sequence according to the colored coding of the notes 33 on the song chart.

To facilitate the playing and/or carrying of the musical instrument described a handle means 34 is provided. As best seen in FIGS. 1, 2 and 3 the handle means 34 comprises a U-shaped member, the leg portions 34A of which are pivotally secured to the opposed side portions of the housing 11. The handle 34 can be readily pivoted to position it in a carrying position, or as seen in FIGS. 2 and 3, the handle means 34 may be rotated to provide a stand or support for the instrument when placed in a horizontal position on a supporting surface. The handle 34 when utilized as a support as seen in FIG. 2 permits the rear end of the housing 11 to be elevated so as to permit better visibility of the musical chart 32 detachably positioned therein.

By providing a plurality of musical charts 34, each representing a different tune, it will be apparent that the charts 32 can be readily substituted one for another within the track 31 provided so as to permit the player to follow the notes of various songs as the wheels are spun accordingly.

With the construction described, it will be apparent that the musical instrument may be rendered readily applicable for use as a musical toy which is pleasing, amusing and safe for use by relatively young children. However, while the instrument 10 is readily applicable for use as a musical toy, it will be readily understood that the same construction may be readily applied to construct a serious musical instrument having one or more octaves.

It has been discovered that the sound generated by the musical instrument 10 described produces notes of long duration as the spinning of the wheels 15 causes the associated striker 25 to repeatedly strike the associated tone bar 26 as the wheels rotate. Thus the sound produced results in an overlapping of the respective musical sounds or notes which produces a most unusual and pleasing audio affect which had not heretofore been known with xylophone type sound bars. When applied to a toy, the instrument is absolutely safe as the moving parts are rendered inaccessible, except for the opening 14 to effect manual spinning of the respective rotating wheels 15.

As best seen in FIGS. 1 and 2, the longitudinal edges 14A defining the opening 14 may be provided with opposed notched out portions 14B to accommodate the respective strikers 25 when radially extended during rotation of the wheel 15. Also the housing 11 may be provided with suitable openings 35 formed therein to permit the sound to emanate out of the housing 11.

In FIGS. 1, 2 and 3, eight rotating wheels 15 are provided, one for each of the respective notes in the musical scale. However, it will be understood that the number of wheels 15 may vary so as to provide a musical instrument having more or less than one octave.

FIG. 7 illustrates a modified embodiment 40 of the invention. In this form of the invention the musical instrument 40 is similar in all respects to that hereinbefore described, with the exception that the housing 41 is formed with a fixed handle portion 42 formed integral therewith and wherein only three rotating wheel members 43 are utilized. It will be understood that the wheel members 43 of FIG. 7 are constructed similar to that described with respect to FIGS. 1 and 3. Also in the embodiment of FIG. 7, no provision is provided for detachably securing a song chart thereto.

In all other respects the construction and operation of the embodiment of FIG. 7 is similar to that described with respect to FIGS. 1 to 5.

From the embodiments disclosed and described it will be apparent that the musical instrument can be played in any position. For example, the musical instrument 10 or 40 can be played by a person while it is being held by the handle, as for example, as seen in FIG. 1, or the musical device 10 or 40 can be played when supported in a horizontal position as seen in FIGS. 2 and 7. The musical instrument can also be played when supported in an overhead position as for example when utilized as a crib toy.

While the present invention has been described with respect to particular embodiments thereof it will be

readily appreciated and understood that variations and modifications may be made without departing from the spirit or scope of the invention.

What is claimed is:

1. A musical instrument comprising:
a base means,
a plurality of rotatable wheels,
means for rotatably mounting said wheels on said base means for independent free wheeling rotation relative to one another,
a tone bar disposed opposite each of said free wheeling rotatable wheels,
a striker means pivotally connected to each of said rotatable wheels,
said striker means being free to pivot relative to its respective rotatable wheel to extend radially outwardly under the influence of centrifugal force to strike said tone bar opposite the rotatable wheel when said wheel is rotated,
each tone bar producing a distinctive overlapping of musical notes when repeatedly struck by the striker means of the adjacent free wheeling rotatable member.

2. A musical instrument comprising:
a pair of complementary housing sections,
means for securing said sections together to define a housing enclosure,
one of said sections having an opening formed therein,
a plurality of rotating wheels,
means for rotatably journaling said wheels so as to be disposed in alignment with said opening whereby said wheels are in independent free wheeling rotation with respect to one another,
a plurality of tone bars disposed within said housing,

means for supporting said tone bars within said housing opposite each of said independent free wheeling rotating wheel means,
each of said wheels having at least one recess formed therein which opens to the periphery thereof,
a striker movably mounted to said wheel within said recess whereby said striker is free to extend radially outwardly of said recess under the influence of centrifugal force imparted thereto as said wheel is rotated to strike said tone bar disposed opposite said wheel,
a song chart having indicia means thereon to represent notes of a given song,
means for detachably securing said chart to said housing,
said wheels being coded to the indicia means whereby said wheels can be actuated in sequence to sound the notes of said song,
a handle means connected to said housing,
and means for pivoting said handle to said housing whereby said handle can be pivoted between a carrying position, and a support position for said housing.
